UNITED STATES PATENT OFFICE.

HERMANUS FRANCISCUS TOL, OF THE HAGUE, NETHERLANDS, ASSIGNOR TO NAAM-
LOOZE VENNOOTSCHAP: MACHINEFABRIEK REINEVELD, OF DELFT, NETHERLANDS,
A CORPORATION OF THE NETHERLANDS.

IRONING MACHINE.

Application filed September 6, 1927, Serial No. 217,786, and in the Netherlands February 17, 1927.

The invention relates to ironing machines of the type in which a flat iron is adapted to reciprocate over a working table, said iron being supported by an arm or other supporting member travelling along a guide member parallel with the table.

5 The main object of the invention is to provide improved means for imparting a reciprocating motion to the iron. To this end according to the invention the reciprocating motion is obtained by a motor driven wheel caused to roll along a longitudinal track connected to the guide member for the iron support.

10 15 It will be clear that in most cases an electric motor will be used, but also water, air or any other suitable driving medium may be applied.

To obtain a reciprocating movement of 20 the iron support one or two running surfaces for the driving wheel may be arranged on the track. If two of such surfaces are arranged, one of them is located above, the other below the driving wheel. By bringing 25 the wheel into contact either with the upper or with the lower surface, the reciprocating movement is obtained.

If only one running surface is arranged 30 the reciprocating movement may be effected by the reversal of the direction of rotation of the motor or by any suitable reversible driving mechanism between the motor and the wheel. As a driving wheel either a gearwheel or a friction wheel may be used.

35 A further object of the invention is to provide a machine in which during the reciprocating motion of the iron the iron may be lifted from or pressed to the table in a convenient way by swinging the guide member for the iron support together with the wheel track and its driving mechanism about an axis parallel to the working table.

With these and other objects in view the invention will be more fully described with 45 reference to the accompanying drawing in which an ironing machine according to the invention is illustrated diagrammatically by way of example.

Fig. 1 is a side elevation of the machine. 50 Fig. 2 is a section on the line II-II in

Fig. 1 with the driving wheel illustrated in dotted lines.

Fig. 3 is a part of the section shown in Fig. 2.

Fig. 4 is a perspective drawing of the 55 belt shifter mechanism.

An iron 1 is suspended from a carriage 2, which is mounted in a support 3 movable transversely to the direction of a working table 4. The support 3 is guided in a frame 60 5. To this end the rear part of the support is provided with a number of rolls 6 with a vertical shaft and a number of rolls 7 with a horizontal shaft. These rolls run in or against angle iron beams 8, 9, 10, 11 and 12, 65 forming together the guide-frame 5.

For the movement of the support along the guide frame 5, upon said support an electric motor 13 is mounted, driving, in a manner which will be hereinafter described, 70 a friction wheel 14, caused to run upon the flat outer surface of the lowermost angle iron 12.

In dependence of the direction of rotation of the wheel, the support with the iron 1 will 75 now travel in one or the other direction of the working table.

The driving of the wheel 14 is effected by means of an open- and a crossed belt 15, 16 from a wide pulley 17 on the motor shaft. 80 These belts run upon two loose pulleys 18, mounted each at one side of a fast pulley 19, upon a shaft 20. This shaft 20 is suspended stationary in an arm 21 from the support 3. The wheel 14 is mounted upon a second 85 shaft 22, bearing in an arm or lever 23 hinged to the shaft 20 and the end of which is connected with the support by means of a spring 24. In this way the periphery of the wheel 14 is pressed in constant contact 90 with the running surface 12. The rotation of the pulley 19 is transmitted to the shaft 22 by the pinion 25 upon the shaft 20 meshing with the gear-wheel 26 upon the shaft 22.

In order to enable the operator to lift 95 the iron from the table or to press it upon the table at will, during its movement the entire guide frame 5, along which the iron-support travels, is pivotally connected with the frame of the machine. The angle-irons 100

8, 9, 10, 11 and 12 are at the ends interconnected by side pieces 27 and 28, rotatable about pivots 29 of the frame (see Fig. 3). These side pieces are also connected with 5 rods 30, which may be moved by treadles 31, 32.

In pushing the treadle 31, the shaft 33, rotates in clockwise direction (see Fig. 2), by which movement the lower ends of the 10 rods 30 are pressed (by means of the rods 34) to the left (in Fig. 2) and the iron is pressed upon the table. On the other hand the treadle 32 causes the same shaft 33 to rotate in anticlockwise direction (by means 15 of the rods 35), by which movement the pressure of the iron on the table is decreased or the iron lifted from the table.

In order to change the direction of the movement of the support, the belts 15, 16 20 are to be shifted alternately from the loose pulleys upon the fast pulley 19. This is effected by means of the belt shifter mechanism illustrated in Fig. 4 of the drawing. Upon the iron 1 is arranged a handle 36 25 shiftable upon a pin 37. This handle, however, may also be secured to the carriage 2, from which the iron is suspended. This embodiment, however, has not been shown for the sake of simplicity. The handle 36 is provided with a lever 38 with a bifurcated 30 end 39. This end engages the end of a rod 40, connected with a shaft 42 by means of cranks 41. The shaft 42 is rotatably supported in the iron 1.

35 By the shifting movement of the handle 36 the rod 40 is swung about the shaft 42. By means of a second fork 43, fixed upon a rotatable shaft 44, this shaft 44 is also swung, said shaft bearing in the support 3 of the iron. Upon the end of said shaft 40 a member 45 is fixed, two projecting parts 46 of which are connected with the support 3 by means of springs 47.

In the member 45 is further provided a 45 slot 48 arranged to engage a pin 49 of the belt shifter 50. Said belt shifter 50 is rotatable about the pivots 51 and displaces the belts by means of the two forks 52.

As soon as the handle 36 is released, the 50 springs 47 automatically pull the member 45 into its middle position, that is to say the position in which the belts run upon the loose pulleys.

On displacing the iron 1 with its carriage 55 2 in the support 3 transversely to the direction of the table the rod 40 slides through the fork 43 without altering the position of the belt shifter.

Finally upon the shaft 44 a second bifurcated crank 53 is fixed, engaging a pin 54 of a crank 55 pivotally connected with the support 3. As soon as the support has reached one of the ends of the guide frame 5 the lower end of this crank 55 comes into 65 contact with a cam 56 or other part of the

frame of the machine. Thereby the crank 55 causes the shaft 44 to rotate and the belt shifter is actuated.

I claim:

1. An ironing machine comprising a support carrying an iron, a guide member along which said support may travel parallel to a working table, a motor mounted on said support, a driving wheel driven by said motor, a longitudinal stationary track parallel to said guide member and means for bringing the periphery of said driving wheel into contact with a running surface upon said track so as to cause the displacement of the support. 70

2. An ironing machine comprising an iron-support, a guide member for said support arranged parallel to a working table, a motor mounted on said support, a friction wheel, power transmitting means, including 75 an open and a crossed belt for driving said friction wheel from said motor, a stationary track with a single running surface for said friction wheel, resilient means for keeping the periphery of said friction wheel in contact with said running surface, a pulley connected to said friction wheel, and means for shifting the open or the crossed belt upon said pulley in order to obtain a reciprocating motion of the iron support. 80

3. An ironing machine comprising an iron support with a motor mounted thereon, a pivoted guide member along which said support may travel parallel with a working table, a longitudinal track rigidly connected 100 with said guide member, a wheel driven by said motor and caused to roll along said track, means for pivotally connecting said guide member with the frame of the machine and means for causing said guide member to swing about the axis of its pivots 105 in a plane transverse to the working table.

4. An ironing machine comprising an iron support, a guide member for said support parallel to a working table, a track parallel 110 to and fixed to said guide member, a shaft on the iron support provided with two loose pulleys and a fast pulley between them, a motor upon said support and provided with a wide pulley for driving said shaft, means 115 for shifting the belts on said pulleys, a second shaft with a friction wheel fixed thereto, driven from said first shaft by a set of gear wheels and bearing in an arm swingable about said first shaft, said arms being connected with the support by springs in such a way that the periphery of the friction wheel is kept in contact with the track. 120

5. An ironing machine comprising an iron, a support therefor, a work table, a 125 guide parallel to said table, said iron being slidably mounted in said guide, a motor, a wheel fixed to said guide and driven by said motor for reciprocating said iron, a pulley connected to said wheel, power trans- 130

mitting means including an open belt and a crossed belt for engaging the pulley, a belt shifter guided in said support, and means for actuating said shifter.

5 6. An ironing machine as claimed in claim 5, said belt shifter having spring means thereon for automatically disengaging said belts from the pulley.

7. An ironing machine as claimed in claim 5, the belt-shifter being provided with means cooperating with cams on the frame of the machine for automatically shifting the belts at the end of each stroke of the iron support. 10

In testimony whereof I affix my signature.
HERMANUS FRANCISCUS TOL.
